BROOM AND MOP COMBINATION

Nelle M. Crofton, Parkersburg, W. Va.

Application January 8, 1944, Serial No. 517,554

2 Claims. (Cl. 15—247)

1

This invention relates to a combination or attachment whereby an ordinary broom or brush is adaptable for sweeping, scrubbing or mopping with one adjustment of condition of the parts.

It is particularly aimed to provide a structure in the nature of a jacket or saddle readily applicable to a broom or brush handle, one which may be laundered, and one to which a different form or forms of scrubbing or mopping elements may be selectively attachable.

It is particularly aimed further to provide a structure wherein the mop cloth will be attached to the saddle in such manner that at the meeting edges of the mop cloth, the brushing surface of the broom will be exposed so that the broom may function normally although having the mop attached thereto.

The more specific objects and advantages will become apparent from a consideration of the description following taken in connection with accompanying drawings illustrating an operative embodiment.

In said drawings:

Figure 1 is a view in elevation showing a broom with my improvements attached thereto, in front elevation;

Figure 2 is a view of the parts of Figure 1 in rear elevation and partly broken away to disclose details;

Figure 3 is a vertical edge elevation;

Figure 4 is a horizontal section taken on the line 4—4 of Figure 1;

Figure 5 is a front elevation similar to Figure 1, but with the mop folded;

Figure 6 is an edge elevation of the parts of Figure 5;

Figure 7 is a perspective view of a broom with a saddle in place thereon; and

Figure 8 is a perspective view of one of the mops, or cloths.

Referring specifically to the drawings wherein like reference characters designate like or similar parts throughout the different views, the invention particularly coacts with an ordinary broom generally designated 10, and 11 being the handle of such broom, 12 being the straws.

A saddle 13 of textile fabric or other flexible material is removably seated on the upper end of the bristles or straws 12 and it has a central opening at 14 through which the handle 11 projects.

Along the lower edge of the saddle, at one side of the broom, it has inclined marginal edges at 15, diverging upwardly and stitched at 16 to the saddle 13 and extending completely around the

2

latter and parallel to the lower edge of the saddle is an attaching strip 17. The said stitching at 16 provides a series of separated loops 18' around the saddle.

5 A scrubbing cloth or mop similar to a turkish towel is disclosed at 18. This cloth may be doubled or of two-ply as shown at 19 in Figure 8, and around the upper edge thereof, an attaching band or tape 20 is stitched as at 21, leaving a plurality of separate textile or other loops at 22.

The said cloth or mop 18 may be detachably secured to the saddle, by means of cords or strings 23 of textile fabric, which may if desired be permanently tied in the loops 18' and then tied 15 in the adjacent loops 22.

It will be noted that due to the inclination of the edges 15 and portions of the band 17, that the free edges of the cloth 18 cross each other above the sweeping end of the broom, as shown 20 in Figure 1, thus exposing a portion of the straws so that when the cloth is attached, the structure may be used as a mop for scrubbing or as a broom for sweeping.

Attention is called to the fact that the cloth 18 25 may be of any suitable construction, for instance be like turkish towels, or may have polishing cloths attached thereto when the same are to be used for polishing purposes and may also have chamois skin attached thereto.

30 When desired, as shown in Figure 6, the lower or free end of the cloth 18 may be doubled back and so held through the engagement of a flexible loop 24 thereon, with a hook 25 suspended by a flexible tab 26. It is to be understood that I am 35 not limited to such means since I may hold the free end of the mop doubled by employing a cord or string like that at 23 in lieu of the loop 24 and hook 25.

Spaced above the band 17 is a band 27 of textile fabric or the like which is stitched in place 40 to the saddle at 28 half way around the saddle, thus leaving half of the web as at 29 unconnected to the saddle. In this large loop 29, I may thread and suspend the cloth or mop when not in use or 45 when sweeping, as suggested in dotted lines in Figure 3.

Various changes may be resorted to provided they fall within the spirit and scope of the invention.

50 I claim as my invention:

1. A structure of the class described comprising a saddle applicable to the upper portion of a broom head, an elongated mop cloth having an upper end wrapped around the broom head and suspended from the saddle, means on the saddle

providing a loop, said cloth being separable on a line extending longitudinally and on the side of the broom head opposite to said loop so that the cloth may be raised to expose the broom head and partially pass through the loop to maintain the broom head exposed, attaching bands on the saddle and cloth, string means separately connecting the bands, and portions of the band on the saddle, disposed above the line of separation of the cloth, being inclined with respect to the free end of the broom head to cause the cloth, when attached thereto, to partly expose the broom head.

2. In a structure of the character described, a saddle engageable over the upper portion of a broom head, an elongated mop cloth folded longitudinally around the broom head and detachably suspended from the saddle and having its longitudinal edges partially overlapping at its suspended end, and means on the saddle providing a loop disposed above the upper edge of the mop cloth and on the side of the broom head opposite to said overlapping edges of the cloth, said mop cloth being adapted to be folded back upon itself and partially passing through said loop for sup-

porting the mop cloth in a spread, inoperative position for exposing the outer end of the broom head.
